INDUCTOR TYPE FURNACE

Filed Aug. 2, 1928

UNITED STATES PATENT OFFICE

EDWIN FITCH NORTHRUP, OF PRINCETON, NEW JERSEY, ASSIGNOR TO AJAX ELECTROTHERMIC CORPORATION, OF TRENTON, NEW JERSEY, A CORPORATION OF NEW JERSEY

INDUCTOR TYPE FURNACE

Application filed August 2, 1928. Serial No. 298,937.

My invention relates to electric furnaces of the pool-surrounding inductor type.

The main purpose of my invention is to reduce the inductor coil heat losses, improving the efficiency of operation of the coil.

A further purpose is to improve the efficiency of a furnace coil which extends below the furnace charge.

A further purpose is to obtain a maximum benefit from a coil surrounding and depending below a furnace pool.

Further purposes will appear in the specification and in the claims.

My invention relates to methods involved and to apparatus by which the methods may be carried out.

I prefer to illustrate a few forms only among various forms in which my invention may be embodied, selecting forms which are practical, efficient and desirable, and which at the same time well illustrate the principles involved.

Figures 1-3 are vertical central sections, largely diagrammatic, showing several forms of my invention.

Figure 2a is a fragmentary section corresponding to part of Figure 3 but showing a different winding.

In the drawings similar numerals indicate like parts.

A considerable part of the energy in operation of electric furnaces of the pool- or charge-surrounding inductor type is dissipated in heat within the inductor coil. This may be reduced for the same number of coil turns by enlarging the cross-section of the turns. However, since radial width of individual turns cannot be increased to advantage from standpoints of conductivity because of the fact that the current through the inductor is largely concentrated along the radially interior portion of the inductor, the increase of the cross-section must be parallel to the axis, increasing the axial length of each turn and of the coil.

There is also of course some limit to the extension of the axial length of the coil which may be desirable, due to many factors, including the objections to handling a furnace of excessive height. Though there is

no hard and fast rule, it has been found by experiment that coil length very desirably approximates the diameter of the coil. On the other hand it may be desirable or necessary to melt or treat the metal in a shallow furnace, and objects to be heated and not melted in quantity sufficient to justify the use of a special furnace may be of much larger diameter or transverse dimension than their length.

So far as I am aware, in the prior treatment of problems of this character the coil has been made in the form of a narrow band surrounding the charge; and except for the present invention it might as well be in this form as an extension of the coil much below the charge would involve the inclusion within the magnetic circuit of an air gap of such length as, by its reluctance, to more than offset the advantage to be gained by extension of the coil.

My invention contemplates the use of a coil appreciably longer than the charge or crucible and the insertion of a magnetic core within the space which would otherwise be unoccupied by the charge in such an extension, in order that the magnetizing current throughout the entire length of the coil may be effective and will be required to drive the magnetic flux through an interior air gap but little more extended than the interior air gap which would be present in case of a short inductor coil. At the same time I wish to call attention to the fact that exterior return for the magnetic circuit can be provided for the furnaces described herein, and external field eliminators can also be applied to it to avoid objections of power factor injury or of interference with outside furnace supports or shells.

Describing in illustration and not in limitation:—

In the structure shown diagrammatically in Figure 1, a shallow furnace pool is shown at 10 as enclosed within a refractory 11 which may or may not be a crucible, and forming either a furnace for melting or additional heating, or a ladle or storage receptacle intended for retention of molten metal during treatment.

About the pool and extending considerably below the limits of the pool I show an inductor 12 whose upper portion only is opposite the pool. Under normal prior conditions of construction, if use of such a coil had been attempted the lower portion of the coil would have presented an open center 13 of high reluctance to the passage of magnetic flux caused by the magnetizing current in the coil and necessitating travel of the lines of force up and down the full length of the coil within it and down and up the full length outside of the coil to complete the return magnetic circuit of the coil.

Within this space 13 I place a magnetic core 14 laminated along vertical lines, as shown at 15, in order to freely allow passage of magnetic lines vertically through the magnetic core in this space.

The magnetic core may be of any desired cross-section, desirably corresponding generally to the cross-section of the space and providing a sufficient cross-section of magnetic material for proper passage of the magnetic lines through the core. This space may be ventilated or cooled if desired.

I am thus enabled to make the coil as long and the cross-section of the individual turn as great as I desire while confining the internal coreless length substantially to the length of the charge or of the charge and bottom refractory.

In Figure 1 no assistance is given to the return of the external lines and the reluctance of this part of the magnetic circuit is increased approximately in proportion to the increase in the length of the coil.

In Figure 2 an external magnetic circuit is provided through laminated strips 16 of magnetic material extending along the coil parallel with its axis and inwardly turned beneath the core 14. Except as access to the top of the charge or pouring may interfere the strips may be turned in correspondingly at their upper ends. Instead of the strips an auxiliary coil 17 can be used to eliminate stray field outside of it and to assist the return magnetic circuit between it and the inductor coil as in Figure 3, where two turns are shown.

Where an auxiliary coil is used it can be short-circuited or operated in series with the main inductor coil as shown in my Patent No. 1,744,983; or can be supplied from an independent source as suggested in Figure 2^a by the leading off of the wires from it.

The strips are rendered very much more effective by the use of an auxiliary coil about them, such as the two turns 17 in Figure 3 or the individual turns 17' in Figure 2^a, causing magnetic flux in the strips corresponding in direction and preferably approximately in strength to the flux caused in them by inductor coil. This approximates a condition of zero reluctance for the return lines, helping

the power factor and eliminating stray external field.

In Figure 3 where coil 17 is shown and the strips are omitted, the coil is effective to eliminate external field beyond it but is not so effective to improve the power factor. However, this makes little difference because the power factor correction can be taken care of by condensers.

The current through the coils should be in phase with the inductor current and may be in series with it as shown.

By my invention I am able to reduce the percentage of heat loss in inductor coils, particularly where the charge is of large diameter and of shallow depth, without sacrificing the advantages of external field elimination and return magnetic circuit power factor improvement which may be applied to the existing inductor coils.

The voltage used will be that suited for the inductor and will not require adaptation to a special flat inductor merely because the melt is of low height.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:

1. The method of reducing the inductor heat losses in a furnace inductor surrounding a charge free from interthreading of transformer iron and much wider than its depth, which consists in increasing the axial length of the inductor much below the bottom of the charge, and in providing a highly permeable path for magnetic lines in the space within the inductor below the charge.

2. The method of reducing the losses of a furnace inductor surrounding a charge free from interthreading of transformer iron and much wider than its depth, which consists in extending the inductor well below the charge, providing a highly permeable path for magnetic lines within the inductor and below the charge, in providing a magnetic return circuit for the flux from the inductor and in electro-magnetically setting up lines of force in the return circuit, assisting the return magnetic flux from the inductor through said magnetic material.

3. The method of reducing the losses of a furnace inductor surrounding a charge free from interthreading of transformer iron and much wider than its depth, which consists in extending the inductor well below the charge, in providing a highly permeable path for magnetic lines in the space within

the inductor and below the charge and in providing magnetic assistance to the return outside the inductor of the flux provided by the inductor.

5 4. The method of reducing the losses of a furnace inductor surrounding a charge free from interthreading of transformer iron and much wider than its depth, which consists in extending the inductor well below the charge, in providing a highly permeable path for magnetic lines within the inductor and below the charge and in electro-magnetically assisting the return flux from the inductor outside of the inductor.

10 5. The method of reducing the losses of a furnace inductor surrounding a charge free from interthreading of transformer iron and much wider than its depth, which consists in artificially extending the inductor below the charge for the purpose of obtaining desirable economy in furnace coil losses and in providing a magnetic path for the additional length of coil beneath the charge.

15 6. An inductor furnace adapted for use about a charge free from interthreading of transformer iron and of considerably larger dimensions across the furnace than longitudinally of it, having an inductor coil about the charge extending much below the charge and a core of magnetic material within the extension of the coil beneath the charge.

20 7. An inductor furnace adapted for use about a charge free from interthreading of transformer iron and of considerably larger dimensions across the furnace than longitudinally of it, having an inductor coil of length not much less than its diameter and approximately on a level at its top with the top of the charge and a magnetic core within the coil and beneath the charge and, from side to side, substantially filling the coil.

25 8. An inductor furnace adapted for use about a charge free from interthreading of transformer iron and of considerably larger dimensions across the furnace than longitudinally of it, having an inductor coil surrounding the charge considerably longer than the depth of the charge and having its extension chiefly below the charge and a magnetic core within the coil beneath the charge and providing room for cooling ventilation between the core and the charge.

30 9. An inductor furnace adapted for use about a charge free from interthreading of transformer iron and of considerably larger dimensions across the furnace than axially of it, an inductor coil considerably longer than the depth of the charge, surrounding the charge and having its extension chiefly beneath the charge and a magnetic core within the coil extension beneath the charge and having ventilating passageways along the core longitudinally of the coil.

35 10. In an inductor furnace adapted to operate upon a shallow charge free from inter-

threading of transformer iron, a container for the charge, an inductor coil having much greater length than the depth of the charge, eccentrically placed in an axial direction with respect to the charge to extend much more below the charge than above the charge and a magnetic circuit for said inductor assisting the magnetic lines within the additional part of the inductor below the charge.

40 11. In an inductor furnace adapted to operate upon a shallow charge free from interthreading of transformer iron, a container for the charge, an inductor coil of much greater length than the depth of the charge having the upper part of the coil surrounding the charge, a core within the inductor below the charge and a magnetic return circuit for the flux caused by said inductor.

45 12. In an inductor furnace adapted to operate upon a shallow charge free from interthreading of transformer iron, a container for the charge, an inductor coil of much greater length than the depth of the charge having the upper part of the coil surrounding the charge, a core within the inductor below the charge and an electromagnetic return circuit for the flux caused by the inductor.

50 13. In an inductor furnace adapted to operate upon a shallow charge, a container for the charge, an inductor coil of much greater length than the depth of the charge having the upper part of the coil surrounding the charge, a core within the inductor below the charge and an electromagnetic return circuit for the flux caused by the inductor comprising magnetic material surrounded by a conductor carrying a current substantially in phase with the inductor current.

55 14. In an inductor furnace adapted to operate upon a shallow charge, a container for the charge, an inductor coil of much greater length than the depth of the charge having the upper part of the coil surrounding the charge, a core within the inductor below the charge and a conductor carrying electric current in phase with the inductor to set up lines of force outside of the conductor counter to those there set up by the inductor.
